[57] CLAIM

The ornamental design for a lipstick case, as shown and described.

DESCRIPTION

FIG. 1 is a front elevational view of a lipstick case showing my new design, the rear and sides being the same;

FIG. 2 is a top plan view thereof;

FIG. 3 is a bottom plan view thereof;

FIG. 4 is an edge elevational view taken by rotating the case forty-five degrees from the front elevational view; and

FIG. 5 is an exploded perspective view thereof.

FIG. 2

FIG. 1

FIG. 4

FIG. 3

FIG. 5
